WRITING INSTRUCTION IMPLEMENT

Margaret L. Harmon, 3837 N. New Jersey St.,
Indianapolis, Ind. 46205

Filed Apr. 21, 1975, Ser. No. 569,866

Term of patent 14 years

Int. Cl. D19—07

U.S. Cl. D19—59

FIG. 1 is a perspective view of a writing instruction implement showing my new design;

FIG. 2 is a perspective view thereof, but with the writing instruction implement being rotated 120° from the position shown in FIG. 1; and

FIG. 3 is a perspective view thereof, but with the writing instruction implement being rotated 240° from the position shown in FIG. 1.

I claim:

The ornamental design for a writing instruction implement, as shown and described.
